J. HUBERT PAGE, OF WHITEWATER, WISCONSIN.

Letters Patent No. 85,954, dated January 19, 1869.

IMPROVED METHOD OF REMOVING AND PROTECTING STORES IN CASE OF FIRE.

The Schedule referred to in these Letters Patent and making part of the same.

To all whom it may concern:

Be it known that I, J. HUBERT PAGE, of Whitewater, in the county of Walworth, and State of Wisconsin, have invented an Improved Mode of Removing and Protecting Stores in Case of Fire; and I do hereby declare that the following is a full, clear, and exact description thereof, reference being had to the accompanying drawings, making a part of this specification, in which—

Figure 1, sheet 1, is an elevation of the front part of a store, which is provided with portable stalls, counters, and show-windows.

Figure 2, sheet 1, is a section taken longitudinally through such a store, in the vertical plane indicated by red lines *z z* in figs. 1 and 3.

Figure 3, sheet 1, is a vertical cross-section taken in the plane indicated by red line *y y* in fig. 2.

Figure 4, sheet 1, is a longitudinal section taken in the vertical plane indicated by red line *y y* in fig. 3, showing two stalls in the act of being removed from the building.

Figure 5, sheet 2, is a perspective view, showing the back part of the stalls provided with hinged shutters, for closing the front and sides of the stall when removed from a building.

Figure 6, sheet 2, is a perspective view of the front part of a stall closed by the shutters.

Similar letters of reference indicate corresponding parts in the several figures.

This invention relates to certain novel improvements, which are designed for protection from fire, and also from theft in case of fire, of stores and goods of all descriptions, which are exposed upon counters, shelves, and in windows, and also for the protection from fire of the books, the safe, and all valuable articles usually kept in counting-rooms of store-houses.

The nature of my invention consists in constructing the shelves, the counters, and the show-windows of a store or business-house upon flooring which is mounted upon wheels or trucks, and supported upon tracks, as will be hereinafter explained, so that, in the event of a fire, and the goods in a store are found to be in danger, the front windows, together with the shelves and counters, and their contents, can all be run out of the store into the street, as will be hereinafter described.

The invention further consists in the arrangement, on one or both sides the central flooring of a store, of rail-tracks, which are adapted to serve as supports and guides for trucks, upon which platforms are constructed, which serve as the foundation and flooring for the counters, the shelves, the counting-room, and the front windows of a store-house, as will be hereinafter explained.

The invention consists, further, in providing shelves, which are mounted upon trucks, and adapted for being removed from a store when desired, with hinged or folding shutters, so applied that, when the shelves are drawn out of the store, they can be enclosed by the shutters, and the goods upon them thereby protected from injury or theft, as will be hereinafter explained.

To enable others skilled in the art to understand my invention, I will describe its construction and operation.

Before describing my invention, I will state that I am aware that the general idea of applying to stores, and other buildings, portable shelves and counters, and constructing the fronts of such stores so that they could be thrown open, and such shelves and counters run out into the street in the event of fire is not new, and therefore I do not desire to claim broadly such arrangement.

In the accompanying drawings—

A A represent the side and back walls of a store, and B, the front wall thereof, which latter is constructed of masonry, metal, or wood, so as to leave spaces on each side of the front central door C for windows D D and hinged shutters a a, arranged beneath the windows, and hinged, so as to close the spaces beneath them, and also to serve, when opened, as shown, in figs. 1 and 4, as inclined planes.

In the centre of the store is a narrow floor, E, constructed upon a foundation, F, as shown in figs. 2 and 3, and on each side of this floor E, level with it, are platforms or floors, G G, which are connected together by chain b, shown in fig. 4, and mounted upon flanged wheels c c, forming trucks, upon which said floors can be moved from place to place.

The two floors G G extend from the front window D to the rear wall of the store, and are fitted into the space between the central floor E and side wall of the store, so as to serve as portions of the flooring of the store for clerks and salesmen, who stand behind the counters.

Beneath the flooring G, on each side of the foundation to the flooring E, sleepers H H are arranged, and suitably secured, and upon these sleepers, rails d d are spiked, which are adapted for receiving the annular grooves of truck-wheels c c.

Upon the front end of the front floor or platform G, on each side of the entrance-door C, the front window D is constructed, so as to fit snugly into the opening made through the front wall to receive it.

Behind this window is the bench or wide sill e, for supporting the goods which it is desired to expose at the front of the store.

The shelves J and the counters K, together with the office or counting-room L, are built upon the portable floors, so that they can all be removed together from the store when necessary.

If the store is a very long one, there may be several independently-supported floors G, connected together by suitable couplings, each floor in the line having its shelves and counters constructed upon it, so that, after the floors, with their counters, have been removed from a store into the street, the parts can be detached, and thus made to occupy less space than they otherwise would.

Beneath the front end of the front floor, on each side of the entrance-way or door C, a staple, g, or its equiv-

alent, is applied, for the purpose of allowing a rope or chain to be readily attached, for drawing out the contents of the store, and in front of this staple is the hinged shutter *a*, which serves to close the opening beneath the window *D*, and which also serves as an inclined plane when turned down, over which the truck-wheels *c* will roll freely in drawing out the goods, as shown in fig. 4.

When the shelves and counters have been removed from a building, as I have above described, it is desirable to provide means for safely enclosing the goods, to prevent them from being injured or stolen, for which purpose I employ folding shutters, as shown in figs. 5 and 6, sheet 2.

These shutters *N N* are hinged to the back corners of the several stalls, and provided with folding sections, *N'*, so hinged to the main shutters that the whole can be folded against the back part of the stall, as shown in fig. 5, and secured in place, out of sight, and out of the way, when the stall is in a store.

When a stall is removed from a store, the shutters can be brought around, as shown in fig. 6, and thus made to enclose and protect the goods upon the shelves and counter of a stall.

When stalls are thus provided with shutters, it is

desirable to construct them with roofs or top coverings, *P*, or to provide hinged coverings for them.

Having described my invention,

What I claim as new, and desire to secure by Letters Patent, is—

1. A portable floor, having show-windows, and which is adapted for supporting the shelves and counters of a store, in such manner that said windows, shelves, and counters can all be removed from a building, substantially as described.

2. The hinged closing-shutters *a*, arranged beneath windows, which are constructed upon portable floors, substantially as described.

3. The construction and arrangement of rail-tracks, on each side of and below the level of the central floor *E*, adapted for supporting trucks, upon which are the shelves and counters, the show-window, and the counting-room of a store, substantially as described.

4. The construction of folding shutters upon portable stalls for stores, substantially as described.

J. HUBERT PAGE.
